UNITED STATES PATENT OFFICE

2,524,735

AXMINSTER NEEDLE DRIVE MECHANISM

Julius H. Pfau, Yonkers, N. Y., assignor to Alexander Smith & Sons Carpet Company, Yonkers, N. Y., a corporation of New York

Application June 29, 1949, Serial No. 101,953

2 Claims. (Cl. 139—123)

1

This invention relates to a drive mechanism for Axminster looms and has for an object to improve the control of the needle at the end of its thrust.

Another object is to prevent the overrunning of the needle at the end of its thrust, particularly at high speeds.

Another object is to provide a needle drive mechanism of the above type in which the needle position with respect to the shuttle contact remains constant regardless of changes in operating speed.

Various other objects and advantages will be apparent as the nature of the invention is more fully disclosed.

Axminster looms customarily include a needle which is advanced entirely across the loom through the warp shed and cooperates at the end of its thrust with a shuttle which is adapted to interloop a selvage thread with the double pick of weft inserted by the needle. Since the needle must be at least as long as the width of the warp shed and its stroke is of a corresponding length, the needle-actuating mechanism possesses considerable inertia, particularly in wide looms. Due to this inertia and the inherent flexibility of the actuating mechanism, it has been found that the final position of the needle at the end of its thrust may vary by a substantial amount when the loom is operating at high speeds from its position at low speed, this variation at times being such as to interfere with the proper functioning of the shuttle.

The present invention overcomes this difficulty by providing snubber means to oppose the advance of the needle, at least during the deceleration periods so that the effect of the flexibility of the drive or lost motion in the driving mechanism is eliminated. The snubber means acts to take up any lost motion in the connections and reverses the effect of the flexibility of the drive so as to retard the needle thrust and bring the needle to rest at a predetermined point regardless of changes in operating speed.

The action of the snubber is further improved by introducing a flexible element at one or more points in the drive mechanism which is arranged to allow the snubber to retard the needle with respect to the drive mechanism. This results in decreasing the rate of change of the needle feed during the periods of reversal which assists in overcoming the inertia effects.

The details of the mechanism and the manner of its operation will be better understood by referring to the following description, taken in connection with the accompanying drawing in which a specific embodiment has been shown for purposes of illustration.

In the drawing:

Fig. 1 is a somewhat diagrammatic side eleva-

2

tion of a drive mechanism embodying the invention;

Fig. 2 is an enlarged detail view showing the construction of the drive and snubber; and

Fig. 3 is an enlarged section taken on the line 3—3 of Fig. 2 showing the resilient connections in the drive mechanism.

Referring to the drawing more in detail, the invention is shown as embodied in an Axminster loom having a needle 10 mounted in a carriage 11 which slides in a track on rails 12. It is to be understood that the length of the needle 10 and of the rails 12 is such that the needle is capable of reciprocating in a path extending through the warp shed of the loom.

The needle may be reciprocated by any suitable motion multiplying mechanism. In the form shown this comprises two sets of movable sheaves 14 and 15 mounted on the upper end of an arm 16 which is pivoted at its lower end by a pin 17 to a link 18 and at an intermediate point by a pin 19 to a link 20. The links 18 and 20 are pivoted to fixed brackets 21 and 22, respectively. The link 20 is the same length as the portion of the arm 16 above the pin 19, and thus causes the upper end of the arm 16 and the sheaves 14 and 15 to reciprocate in a straight line.

A cable 25 is connected at one end to the carriage 11 and extends around a fixed pulley 26, thence back and forth several times between movable sheaves 14 and a set of stationary sheaves 27 and its other end is anchored to a frame 28 by means of a rod 29 and is held under tension by a spring 30.

A cable 32 is connected at one end to the carriage 11 and extends around a fixed pulley 33, thence back and forth several times between movable sheaves 15 and a set of fixed sheaves 34 and its end is anchored to the frame 35 at 36. The arrangement is such that reciprocation of the upper end of the arm 16 causes the cables 25 and 32 to reciprocate the carriage 11 in its track along the rails 12, the sets of sheaves serving to multiply the motion by the required amount. The sheaves 14 and 15 have been shown as offset for clearness. In practice they would be mounted coaxially on the arm 16. It is also to be understood that other motion multiplying drive means may be used, such as a rack and pinion driving a drum on which the cables 25 and 32 may be wound.

The mechanism thus far described is of standard type and only so much thereof has been shown as is necessary to an understanding of the invention.

For driving the arm 16 there is provided a drive shaft 40 which is driven by a suitable source of power and is keyed to a crank arm 41. A driving link 43 is pivoted at one end by a pin 44 to the crank arm 41 and at its other end is pivoted to the pin 19.

60

As illustrated in Fig. 3, the driving link 43 is formed in two parts 45 and 46 which are connected by a flexible coupling. The part 45 is formed at its forward end with an annular flange 47 having a shoulder 48 against which the outer metal ring 49 of a flexible coupling is secured by a snap ring 50. The flexible coupling comprises outer and inner metal rings 49 and 51 bonded to an intermediate rubber ring 52 and is of the type commonly used for vibration mountings. The rearward end of the part 46 is held in the inner metal ring 51 which is seated against a shoulder 53 and clamped by a nut 54.

The rearward end of the part 45 is shown as forked and secured to the pin 44 which is journalled in the inner ring 58 of a vibration mounting having inner and outer metal rings 58 and 59 bonded to an intermediate rubber ring 60. The outer metal ring 59 is mounted in the crank arm 41.

The forward end of the part 46 carries a similar vibration mounting having inner and outer metal rings 64 and 65 bonded to an intermediate rubber ring 66. The pin 19 is journalled in the inner metal ring 64 and extends through the double arm 16 and through the link 20.

It is understood that one or more of the vibration mountings may be omitted if sufficient flexibility is obtained by the inherent lost motion of the couplings.

The snubber means is shown as comprising a fluid pressure cylinder 68 pivoted at one end to a fixed bracket 70 and having a piston 72 on a piston rod 74 which extends from the free end of the cylinder 68 and is pivotally connected by a pin 76 to the arm 16 at a point above the pin 19, although the point of connection will depend upon the stroke of the cylinder 68. If a shorter cylinder is used, the point of connection will be correspondingly lowered on the arm 16. In any event the snubber means should be located beyond the flexible couplings or beyond the principal source of lost motion in the drive.

The cylinder is provided with an open valve 78 at its free end and with a vent 80 at its pivoted end connected to a flap valve 82 and an adjustable valve 84. The flap valve 82 opens inwardly to allow free return of the piston and the adjustable valve 84 provides for a controlled cushioning or snubbing action on the advance of the piston. If desired the valve may be set to retain a part of the compression for restoring the energy of compression during the return stroke of the piston.

In the operation of this drive the crank arm 43 rotates at a constant rate and the arm 16 and needle carriage are reciprocated thereby. During the portions of drive cycle where deceleration occurs the inertia of the needle and of the drive mechanism tends to stretch the cables, flex the driving arms, and the lost motion of the connections, which may be due to the looseness of the couplings or to the resilience of the vibration couplings above described, is reversed from that occurring during acceleration periods.

In the present construction the piston 72 serves as a snubber to take up the lost motion during the deceleration of the needle thrust. This not only eliminates the jerkiness due to reversal of the lost motion, but tends to retard the needle so that a positive driving force is required on deceleration as well as on acceleration.

The rate of change in feed at the instant of

reversal is reduced below that corresponding to the normal drive motion and the needle position at time of shuttle contact is made practically independent of loom speed. Hence the loom may be operated at higher than normal speeds without difficulty. The flexibility of the drive is controlled to obtain a positive needle position at reversal.

The valves may be adjusted to produce the required cushioning effect and the cylinders automatically produce greater cushioning pressure at higher speeds. Of course another cylinder may be used on the side corresponding to the retracted position of the needle or a single double acting cylinder may be used if desired.

It is to be understood that the invention is not restricted to the particular type of drive shown, but may be used with other types of motion multiplying mechanism and is useful in general for reducing the rate of change and reversal of reciprocating members. Various adaptations will be apparent to a person skilled in the art.

What is claimed is:

1. In an Axminster loom having a needle adapted to be reciprocated to lay double weft shots through a warp shed, drive mechanism connected to reciprocate said needle, said mechanism comprising a pivoted arm, motion multiplying means connecting said arm to actuate said needle, a continuously rotating drive member, connecting members connecting said drive member to cause reciprocating movement of said arm, and a fluid pressure cylinder having one end pivotally mounted and having a piston rod extending through the free end thereof and connected to said pivoted arm, a piston attached to said rod, and vent means in said cylinder arranged to cause said piston to oppose the movement of said pivoted arm during periods of deceleration.

2. In an Axminster loom having a needle adapted to be reciprocated to lay double weft shots through a warp shed, drive mechanism connected to reciprocate said needle, said mechanism comprising a pivoted arm, motion multiplying means connecting said arm to actuate said needle, a continuously rotating drive member, connecting members connecting said drive member to cause reciprocating movement of said arm, and a fluid pressure cylinder having one end pivotally mounted and having a piston rod extending through the free end thereof and connected to said pivoted arm, a piston attached to said rod, and vent means in said cylinder arranged to cause said piston to oppose the movement of said pivoted arm during periods of deceleration, said vent means including an adjustable valve for controlling the effect of said cylinder.
